UNITED STATES PATENT OFFICE

CHARLES PECKERMAN, OF NEW YORK, N. Y.

DESIGN FOR AN IMITATION CHRISTMAS TREE

Application filed July 2, 1931. Serial No. 40,399. Term of patent 14 years.

To all whom it may concern:

Be it known that I, CHARLES PECKERMAN, a citizen of the United States, and residing at New York, in the county of New York and State of New York, have invented a new, original, and ornamental Design for Imitation Christmas Tree, of which the following is a specification, reference being had to the accompanying drawings, forming part hereof.

Fig. 1 is a front elevational view of an imitation Christmas tree, showing my new design, and

Fig. 2 is a top plan view thereof.

I claim:

The ornamental design for an imitation Christmas tree substantially as shown.

CHARLES PECKERMAN.
